US0D1088206S

(12) **United States Design Patent** (10) **Patent No.:** **US D1,088,206 S**
(45) **Date of Patent:** **** Aug. 12, 2025**

(54) **PORTABLE ATMOSPHERIC WATER GENERATOR DEVICE**

(71) Applicant: **Spout Ventures Inc.**, West Hollywood, CA (US)

(72) Inventors: **Reuben Paul Vollmer, II**, Venice, CA (US); **Tyler Breton**, Los Angeles, CA (US); **Fred Bould**, Menlo Park, CA (US); **Calvin Patrick Henderson**, San Francisco, CA (US); **Jamie Starr Perin**, San Francisco, CA (US)

(73) Assignee: **Spout Ventures Inc.**, West Hollywood, CA (US)

(**) Term: **15 Years**

(21) Appl. No.: **29/874,596**

(22) Filed: **Apr. 21, 2023**

(51) LOC (15) Cl. **23-01**

(52) U.S. Cl.

(57) **CLAIM**

The ornamental design for a portable atmospheric water generator device, as shown and described.

DESCRIPTION

FIG. 1 is a top front right perspective view of a portable atmospheric water generator device in a combined configuration, showing our new and ornamental design;

FIG. 2 is a front side view thereof;

FIG. 3 is a back side view thereof;

FIG. 4 is a left side view thereof;

FIG. 5 is a right side view thereof;

FIG. 6 is a top side view thereof;

FIG. 7 is bottom side view thereof;

FIG. 8 is a top front right perspective view of a pitcher of the portable atmospheric water generator device in a separated configuration; and,

FIG. 9 is a top front right perspective view of a machine of the portable atmospheric water generator device in the separated configuration.

The broken lines illustrate portions of the portable atmospheric water generator device form no part of the claimed design.

1 Claim, 9 Drawing Sheets
